(57) **CLAIM**

The ornamental design for a inclined sorter, as shown and described.

DESCRIPTION

FIG. 1 is a front, right side, top perspective view of a sorter showing my new design;

FIG. 2 is a front, left side, top perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof; and,

FIG. 9 is a sectional view thereof taken along line 9-9 in FIG. 3.

The broken lines in the drawings are included for the purpose of showing portions of the sorter that form no part of the claimed design.
